BURR R. SKINNER, OF ABERDEEN, SOUTH DAKOTA, ASSIGNOR OF ONE-HALF TO
ROBERT LIEBRICH, OF INDIANAPOLIS, INDIANA.

NECKTIE FORMER AND HOLDER.

1,414,529.

Specification of Letters Patent.

Patented May 2, 1922.

Application filed October 30, 1920. Serial No. 420,699.

To all whom it may concern:

Be it known that I, BURR R. SKINNER, a citizen of the United States, residing at Aberdeen, in the county of Brown and State of South Dakota, have invented a new and useful Necktie Former and Holder, of which the following is a specification, reference being had to the accompanying drawings, and to the letters and figures of reference marked thereon.

This invention relates to a holder on which a neck-tie may be formed artistically and held in connection with a shirt collar by means of a collar button commonly used in the neck band of shirts or similar garments, the invention having reference more particularly to a combined former and holder that is adapted to be adjustably connected to a collar button to hold a neck-tie in proper relation either to a high or to a relatively low turn-down collar.

An object of the invention is to provide an improved neck-tie former and holder which shall be so constructed as to permit a neck-tie to be easily formed or artistically hung thereon, and whereby the neck-tie may be easily and quickly secured in connection with a garment collar or to be easily removed from the collar.

Another object is to provide an improved neck-tie former and holder which shall be of such design as to be adapted to be constructed of few and simple inexpensive parts, and especially of scrap sheet metal, and of flexible character permitting the user to readily bend and re-shape the former and holder to the curvature of different sizes of collars or neck bands.

A further object is to provide an improved neck-tie former and holder which shall be so constructed as to be adapted to be firmly secured in different positions to a collar button, and on which a "string-tie" or a "four-in-hand" neck-tie may be artistically formed and held in place in connection with a collar, and which shall be adapted to be durable and economical in use.

With the above-mentioned and other objects in view, the invention consists in a specifically novel device on which a neck-tie may be looped and securely held, the device having means whereby to secure it in different positions on a collar button, the invention consisting further in the parts and combinations and arrangements of parts as

hereinafter particularly described and further defined in the accompanying claims.

Referring to the drawings, Figure 1 is a fragmentary representation of a shirt and collar to which a neck-tie is applied to represent a "four-in-hand" style as formed on the improved former and holder; Fig. 2 is a front elevation of the improved former and holder; Fig. 3 is a rear view showing the formation of the neck-tie on the former and holder which is partially visible as it projects from the neck-tie, hidden portions of the holder being shown by broken lines; Fig. 4 is a rear elevation of the improved former and holder partially broken away; Fig. 5 is a fragmentary section on the line V—V in Fig. 2; Fig. 6 is a front view of a portion of a collar and the improved former and holder connected with the front collar button of the garment, and, Fig. 7 is a front elevation of the improved former and holder slightly modified as to details.

In the several figures of the drawings corresponding or like reference characters indicate corresponding or like features or details of construction herein referred to.

A practical embodiment of the invention consists, generally, in a stem adapted to be vertically supported on a collar button to support a neck-tie and having arms or horns to engage a collar to prevent the stem from tilting on the collar button and to hold the neck-tie steadily in place on the front of a shirt or garment 1 having a neck band 2 on which is a turn-down collar comprising a band or inner portion 3 and an outer or turned-over portion 4, the band portion of the collar being connected to a back or rear button 5 and a front button 6, the folded portion 7 of the collar being at different heights from the collar button holes in different styles of collars as will be understood, and therefore the stem is adapted to be adjustably connected to the collar button as may be desired with the different collars.

More specifically, as preferably constituted the combined former and holder comprises a head-bar 8 designed to be horizontally arranged in use and having upwardly curved arm shoulder portions 9 and 10, main arm portions 11 and 12 divergently each to the other and having curved portions 13 and 14 thereon from which finger portions 15 and 16 extend, outwardly and upwardly with respect to the main arm por-

tions, the finger portions having rounded ends 17 and 18 respectively. The stem comprises a lock-bar 19 fixed to the head-bar 8 adjacent to the middle portion thereof, preferably by means of a rivet 20 and solder 21, the lock-bar extending downward approximately at right angles to the head-bar with one edge thereof approximately on a line or plane intersecting the middle 10 of the head-bar, said edge portion having notches or recesses 22, 23 and 24 therein to receive the shank of the front collar button, and the lock-bar preferably has a beveled end 25 to be guided on the shank of the collar button. The stem comprises also a companion lock-bar 26 which is connected at one end with a pivot 27 that is connected to the head-bar 8 beyond the middle portion thereof from the rivet 20. The pivot preferably 20 is hollow so as to be slightly elastic to enable it to hold the lock-bar closely and frictionally to the head-bar yet permitting the lock-bar to be manually moved pivotally. The inner edge of the lock-bar 26 which is 25 opposite to the lock-bar 19 has notches or recesses 28, 29 and 30 therein opposite to the notches in the companion lock-bar to receive the shank of the collar button, and the pivoted lock-bar preferably has a beveled inner edge 31 to be guided on the shank of the collar button. Thus formed the lock-bars have pointed ends at their outer edges between which the user may place his finger to move the pivoted lock-bar 35 away from the collar button.

In some cases the lock-bar 19 is integrally connected as at 32, Fig. 7, with the lower edge of the head-bar 8.

In practical use a suitable neck-tie is 40 folded near its middle portion and the middle portion arranged horizontally across the front of the head-bar to form a bow front 33, one adjacent portion is carried around one horn or arm to form a loop 34 and thence is drawn down over the horn and between the bow front and the head-bar to 45 form a pendant 35, and the remaining portion of the tie is carried over the opposite horn to form a loop 36 and thence downward 50 behind the bow front 33 and at the front of the pendant 35 to form a front pendant 37. The neck-tie being securely

connected to the head-bar and the arms or horns of the device, the pivoted lock-bar is swung away from the companion lock-bar, 55 the assembly pushed under the ends of the outer portion of the collar until the ends of the arms or horns come in contact with the folded portion 7 of the collar and the shank of the collar button is received in one of the 60 notches in the relatively fixed lock-bar, after which the pivoted lock-bar is moved over to receive a portion of the collar button shank in one of the notches therein, so that the collar button shall hold the stem in place 65 and prevent the neck-tie from slipping downward. The pivoted lock-bar may be readily moved to release the stem from the collar button when it is desired to remove the neck-tie from place. 70

Having thus described the invention, what is claimed as new is,-

1. A neck-tie former and holder comprising a head-bar having a lock-bar fixed thereon and a lock-bar pivoted thereto, the lock-bars normally extending from the lower edge of the head-bar at right angles thereto and having each a plurality of notches in the inner or adjacent edges thereof, and two curved arms on opposite ends respectively 75 of the head-bar extending upwardly beyond the upper edge thereof and outwardly each away from the other.

2. In a neck-tie former and holder, the combination of a flat and laterally flexible 85 head-bar, two laterally flexible main arm members extending upwardly from opposite ends respectively of the head-bar, two laterally flexible fingers extending from the arm members outwardly each away from the 90 other and having each a rounded end, a lock-bar fixed to the head-bar adjacent to the middle portion thereof and extending downward therefrom, the lock-bar having a plurality of notches in one edge thereof, 95 and a lock-bar pivoted to the head-bar and having a plurality of notches in one edge thereof.

In testimony whereof, I affix my signature in presence of two witnesses.

BURR R. SKINNER.
